ROLAND L. FLINN, OF ALBERTON, MONTANA.

ALARM FOR AIR-BRAKE SYSTEMS.

1,387,002.

Specification of Letters Patent. Patented Aug. 9, 1921.

Application filed February 3, 1921. Serial No. 442,121.

To all whom it may concern:

Be it known that I, ROLAND L. FLINN, a citizen of the United States, residing at Alberton, in the county of Mineral and State 5 of Montana, have invented certain new and useful Improvements in Alarms for Air-Brake Systems, of which the following is a specification.

This invention relates to alarms for air 10 brake systems the primary object of which is to provide a device which will automatically sound an alarm as soon as there is a break in the air line or lack of pressure due to failure of the pumps to operate, or diminution of the power from any cause.

Another object of the invention is to provide a simplified mechanism which may be conveniently connected to the air line at any desired point and is equipped with a whistle 20 or other desired audible signal means which may be placed in the cab of the train, or otherwise positioned where it will be readily heard by a member of the train crew.

The above and other objects of this invention will be in part described and in part 25 understood from the following description of the present preferred embodiment taken in connection with the accompanying drawings, wherein:

30 The figure is a vertical sectional view of the device constructed in accordance with this invention, a portion thereof being shown in side elevation.

In the drawings, a casing 1 is provided, 35 which in this instance is shown to be of a cylindrical configuration, a portion of the bottom wall thereof being straight to provide an annular seat 2, the central portion of the wall being inclined downwardly, as indicated at 3, and issues into an externally 40 screw threaded inlet terminal 4. The inlet terminal is adapted for connection with the train line and is tubular to permit the passage of air therethrough and into the casing 45 in a manner hereinafter described. The upper inner periphery of the casing is provided with screw threads which complement screw threads formed upon a cap 5 and are engaged therewith. A laterally extending

50 port 6 is formed on the outer periphery of the casing, approximately midway the ends of the latter and is in communication with the interior of the casing. This port has external screw threads formed thereon which 55 in turn are engaged with a conduit 7, which is carried by a reservoir 8. The casing is

equipped with a port 9 on the side opposite to that which carries the port 6, and is in communication with the interior of the casing and also with an alarm mechanism 10, 60 which in this instance consists of a whistle. A shaft 11 is concentrically arranged in the casing 1, and has screw threads thereon, remote from its lower end, an upper piston 12. A lower piston 13 is screw threaded 65 upon said shaft in proximity to the lower end of the latter. The said lower piston is tubular and has the upper end thereof arranged adjacent to but spaced from the upper piston 12. The said upper piston is 70 provided with an annular way 14, which is in communication with the ports 6 and 9 when the shaft 11 is in its lowermost position as shown in the drawings.

Interposed between the cap 5 and the 75 upper piston 12 is a coil spring 15, the lower end of which is engaged with a cup 16 carried on the upper face of said piston 12. The opposite end of the spring is in engagement with a cup 17 which is arranged on the shaft 80 11 and is engaged against one end of a gland 18. The said gland is provided with external screw threads which engage corresponding threads formed centrally in the cap 5. The bore of the gland is smooth 85 throughout and has the shaft 11 slidably mounted therein.

A puppet valve 19 is mounted upon the shaft 11 between the closed end of the piston 13 and the piston 12. Normally, the valve 90 lies in snug engagement with the closed end of the piston 13. The latter, however, is provided with one or more openings, such as that indicated at 20 which permit ingress of air through the inlet terminal 4 and into 95 the piston 13 for the purpose of elevating the puppet valve. Since the said valve is slidably on the shaft 11 it is apparent that as soon as the air pressure through the terminal 4 is cut off, the puppet valve will gravitate into engagement with the closed end of the piston.

In use of this device, the spring 15 will be tensioned to a certain point through the manipulation of the gland 18. Consequently, pressure of air from the train line through the terminal 4 and into the casing must be of a predetermined pressure in order to elevate the pistons 12 and 13 against the resistance of said spring 15. 110 The air in entering the casing passes through the opening or openings 20, thereby

elevating the puppet valve 19 into engagement with the piston 12 so as to elevate the entire structure consisting of the shaft 11 and pistons 12 and 13. After having elevated the pistons 12 and 13 to a predetermined point, the air will be permitted to pass into a bypass 21, one end of which communicates with the casing and the opposite end with the port 6. Consequently, a small 10 volume of air will pass through the port 6 and into the reservoir 8 which latter may be of any desired size. As soon as the pressure of air through the terminal 4 is cut off, the pistons 12 and 13 will be returned to 15 their normal positions by the expansive action of the spring 15, thereby bringing the annular way 14 into communication with the ports 6 and 9. The air contained in the reservoir 8 will be permitted to return into 20 the casing through the way 14 and ultimately passes out through the way 9 for blowing the whistle 10. If the pressure of air through the terminal 4 should merely be slightly diminished, the air coming 25 through the terminal 4 and passing through the openings 20 will be insufficient to operate the puppet valve 19 against the piston 12, consequently the air will travel beyond the periphery of the puppet valve as indicated at A in the drawings and from thence 30 will pass directly through the port 9 so as to cause a continuous blowing of the whistle.

In order to prevent casual displacement of the piston 13, a nut 22 is threaded on the 35 lower end of the shaft 11 which may, of course, be readily removed to permit removal of the piston when desired. Also a vent opening 23 is formed in the wall of the casing 1, preferably between the cap 5 and piston 12. 40 Moreover, in order to prevent casual displacement of the cap 5 a set screw 24 is arranged through the casing and engages the cap.

Various changes may be made in this device, especially in the details of construction, proportion and arrangement of parts 45 without departing from the spirit and scope of the invention as covered by the appended claims.

What is claimed is:

1. An alarm for air brake systems including a casing engageable with the air line and equipped with means movable under air of predetermined pressure to permit the exhaust of a certain volume of the 55 air from said casing, a container in communication with said casing to receive the air exhausted from the latter, and alarm mechanism in communication with said casing and said container to permit passage of 60 air from said container into said mechanism for sounding the alarm when the air pressure into the casing is insufficient to operate said means.

2. An alarm for air brake systems including a casing equipped with pistons movable in sequence by pressure of air to permit exhaust of a portion of the air through the casing, a container in communication with said casing to receive the air exhausted from the latter, and alarm means in connection with the casing and operable by the air pressure whereby diminution of the air supply will permit return of the air from said container and into said alarm means for operating the latter.

3. An alarm for air brake systems including a casing engageable with the air line and equipped with pistons movable into an open position under a predetermined pressure of 80 air to permit exhaust of a fractional portion of the air flowing into the casing, a container in communication with the casing to receive the air exhausted from the latter, one of the pistons having an annular way 85 formed therein which communicates with the container when the piston is closed, and a signal adapted to communicate with said way to permit direct passage of air from said container through the way and to the 90 signal for operating the latter.

In testimony whereof I affix my signature in presence of two witnesses:

ROLAND L. FLINN.
